DIFFUSER

Amiel L. Faiver, Buena Park, Calif., assignor to
Diffuser Corporation, Fullerton, Calif., a cor-
poration of California

Application July 22, 1936, Serial No. 91,862

1 Claim. (Cl. 299—87)

This invention relates to diffusers.

The general object of the invention is to provide an improved diffuser by means of which various chemicals can be projected into a space to be treated.

Another object of the invention is to provide a novel nozzle for a diffuser.

An additional object of the invention is to provide a novel blow-off valve for a diffuser.

Another object of the invention is to provide a diffuser including a novel container having novel vessel supporting members therein.

Another object of the invention is to provide a novel mechanism for controlling the amount of chemical discharged by a diffuser.

Other objects and the advantages of the invention will be apparent from the following description taken in connection with the accompanying drawings, wherein:

Fig. 1 is a top plan view of a diffuser embodying the features of my invention;

Fig. 2 is a central, sectional view taken on line 2—2 of Fig. 1;

Fig. 3 is a fragmentary, sectional view taken on line 3—3 of Fig. 2;

Fig. 4 is an enlarged, fragmentary, sectional view showing the discharge nozzle and associated parts;

Fig. 5 is a section taken on line 5—5 of Fig. 4;

Fig. 6 is an enlarged, fragmentary side elevation showing the diffuser;

Fig. 7 is a central, sectional view showing the blow-off member; and

Fig. 8 is a side elevation of the sleeve.

Referring to the drawings by reference characters I have shown my invention as embodied in a diffuser which is indicated generally at 10. As shown the diffuser includes an outer container 11 which may be made of metal or other suitable material and which may be provided with a side seam 12 and with a bottom 13 secured thereto. The bottom may be provided with bosses 14 upon which the container is supported. The container is shown as provided with a bail 14' and with a closure 15 which has a sliding fit with the container so that the closure is removable.

The container 11 is provided with a plurality of viewing apertures 16 and with a lining 17 which may be made of "Cellophane" or similar material. Within the container I arrange a fixed shelf 18 which includes a flange 19 and supporting ears 20 which may be riveted as at 21 to the container and above the shelf 18 I provide a second shelf 22 which includes a bottom 23 having sides which are pivoted as at 24 so that the shelf

may swing to a position parallel to the shelf 18. The shelves 18 and 22 are employed to support vessels which hold chemicals. The shelf 18 is intended to support a relatively long chemical holding vessel while the shelf 22 when lowered to the dotted line position in Fig. 2 serves to hold a shorter vessel. As shown in the drawings the shelf 18 is employed to hold the chemical holding vessel 25 which has a threaded cap 26 thereon. This cap is provided with a central aperture 27. The upper end of the vessel 25 projects through an aperture 28 in the closure 15.

Disposed within the container 11 I show a steam generating device indicated generally at 29. As shown this device includes a receptacle 30 which may be made of glass and which has a metallic lid 31 mounted thereon. The lid is provided with suitable apertures in which grommets 32 are mounted. These grommets 32 are preferably made of vulcanized fiber, or similar insulating material and through the grommets electrodes 33 extend. The electrodes 33 include terminal portions 34 adapted to be disposed below the normal water level 35 in the receptacle 30.

Mounted on the receptacle 11 I show a discharge tube 36 which includes a lower flange 37 which serves to hold the tube in place on the lid 31. The tube passes through a grommet 38 on the closure 15 and is provided with a circumferentially extending groove 39 which is intersected by apertures 40 which afford communication between the interior of the tube and the groove. Mounted within the tube 36 I provide a blow-off valve member 41 which threadedly engages the interior of the tube and which includes a lower aperture 42 and a hexagonal valve member 43 which slidably fits in a cylindrical aperture 44. The aperture 44 communicates with an outlet 45.

When the pressure within the container 29 becomes excessive the valve member 43 is moved from its seat to relieve this excessive pressure.

Mounted upon the tube 36 I show a sleeve 46. This sleeve is held in place by a flange 47 on the valve member 41 and the sleeve has an aperture in which a nozzle 48 is mounted. This nozzle 48 communicates with the groove 39 previously mentioned. The construction is such that steam generated in the container 29 passes out through the nozzle 48 and through a discharge member 49 on the end of the nozzle. Mounted within the nozzle I show an injector tube 50 which tube passes through the aperture 27 previously mentioned and extends to a location near the bottom of the chemical holding vessel 25. The injector tube 50 passes through the wall of the nozzle 48 as 55

- at 51 where a leak-tight joint is provided and extends to a location 52 at the end of the discharge member 49. The length of the downwardly extending portion of the injector tube will be varied 5 to suit the conditions and when long vessels are employed as shown in Fig. 2 the tube will be of the length shown. If shorter vessels are employed then the length of the lower portion of the tube 50 will be correspondingly decreased.
- 10 The nozzle 48 adjacent to the discharge member 49 is engaged by a plurality of screws 53 shown as three in number which are threaded in apertures in the nozzle and which engage the end of the injector tube. By releasing two of the 15 screws and tightening the third screw the position of the injector tube 50 relative to the outlet of the end 52 may be shifted thus shifting the eccentricity of the tube 50 with respect to the nozzle so that the injection effect may be varied.
- 20 With my invention when the steam generating apparatus is operated the heat generated therein passes through the walls of the generating container thus heating the chemical holding vessel, also the steam passing through the nozzle warms 25 the latter thus causing the material drawn into the injector to be heated. Thus the high temperature is maintained by the chemicals being employed so that a better distribution is secured.

My device is adapted for use with various types of chemicals and may be used for treating various spaces in order to destroy flies, mosquitoes, etc. My device may be employed with solutions containing pyrethrum or other materials as desired. 5

From the foregoing description it will be apparent that I have invented a novel diffuser which can be economically manufactured and which is highly efficient in use.

Having thus described my invention I claim: 10

In a diffuser, a chemical holding vessel, a steam generating device, said steam generating device including a receptacle, a lid on said receptacle, a discharge tube on said lid, a sleeve removably mounted on said tube, a closure member threaded 15 within said tube and having a flange thereon engaging said sleeve to normally prevent removal of the sleeve, said tube having apertures therethrough, said sleeve having a nozzle therein communicating with said apertures, an injector tube 20 extending into said vessel, said injector tube piercing said nozzle intermediate the length of the nozzle, said injector extending into and along the interior of said nozzle, said nozzle having an outlet, the diameter of said outlet being greater 25 than the exterior diameter of said injector tube.

AMIEL L. FAIVER.
